To all whom it may concern:

Be it known that I, Hildreth Lange Dexter, a citizen of the United States, residing at New York city, in the county of New York and State of New York, have invented a new, original, and ornamental Design for a Bottle, of which the following is a specification, reference being had to the accompanying drawing, forming a part thereof.

Both sides of the bottle are provided with depressed panels as shown in Figure 2. The back of the bottle is plain and is the same as the front except that there is no portion extending from it over the top.

I claim:

The ornamental design for a bottle, as shown and described.
